UNITED STATES PATENT OFFICE.

JOHN F. WALLACE, OF PITTSBURG, PENNSYLVANIA.

CAR-COUPLING.

SPECIFICATION forming part of Letters Patent No. 253,246, dated February 7, 1882.

Application filed November 17, 1881. (No model.)

To all whom it may concern:

Be it known that I, JOHN F. WALLACE, of Pittsburg, in the county of Allegheny and State of Pennsylvania, have invented a new and useful Improvement in Car-Couplings; and I do hereby declare the following to be a full, clear, and exact description thereof, reference being had to the accompanying drawings, forming a part of my specification, in which—

10 Figure 1 is a plan view of two opposite and meeting draw-heads, showing my invention. Fig. 2 is a longitudinal sectional view of one of the draw-heads. Fig. 3 is a view of the face of the draw-head. Fig. 4 is a side elevation of the draw-head.

15 Like letters of reference refer to like parts wherever they occur.

My invention relates to certain improvements in that class of safety car-couplings wherein the coupling is effected by introducing the link through a side opening in the draw-head, and has for its object to re-enforce the draw-head and provide a guide for the coupling-link, for which purpose a brace is provided on the slotted side of the draw-head, and guide-lugs are arranged in front of and in line with the hole of the coupling-pin, all as will hereinafter more fully appear.

I will now describe my invention, so that others skilled in the art may manufacture and use the same.

In the drawings, *a* represents the face of the draw-head, in which is the opening or mouth *b*, through which passes the coupling-link *c*. This opening *b* extends through one side of the draw-head, and flares on the lip *d*, so as to form an opening, *b'*, in the side of the draw-head. On the upper and lower side of the opening *b* are formed bulges or projections *e*, which are designed to prevent one draw-head becoming wedged within another, and also to act as guides to the link and supports to the pin. On the side of the draw-head on which is the opening *b'* is a brace, *f*, which is designed to overcome any weakness imparted to that side of the draw-head by the opening, and which may extend any desired length along the side. The pin-hole *g*, which runs through the draw-head, is situated as near the face of the same as the strength of the metal will allow. In the back of the pin-hole *g* is a recess, *g'*, which acts as a rest or stop for the pin *h*. This stop is situated

low down, so as to hold the pin in as nearly a perpendicular position as possible.

The operation of my improved coupling is as follows: The cars being situated so that their draw-heads touch each other, the link *c* is inserted, from the side of the draw-head, through the side opening, *b'*, into the mouth *b* of the draw-head on the opposite car. The pins are then inserted and the cars are coupled. They may be uncoupled, when the draw-heads are touching, in a like manner, the pin being removed, and, if desired, the link may be withdrawn from the draw-heads. The projections *e*, while they are designed partially to prevent the draw-heads from jamming together, also serve as a guide to the link guiding it, so that the link shall pass under the pin-hole so as to prevent miscoupling, and also as a support to the coupling-pin. When the cars are coupled, by moving them so that they come together the pin *h* is placed in the hole *g* so that the pin shall rest on the stop *g'*, and as soon as the link enters the mouth of the draw-head and the cars come together the jar causes the pin to fall through the link *c* into the opening *g* in the lower portion of the draw-head. This stop *g'* is situated low down, so that the jar will not cause the pin to fall out of the pin-hole *g*. This opening *g* being placed near the front of the draw-head, cars having their draw-heads on different planes can be coupled together by a plain link. In order to allow of the pin-hole to be so situated, the draw-head is made strong by a sufficient thickness of metal above and below the mouth *b*, and also on the side of the face of the draw-head opposite to the opening *b'*.

The advantages of my invention are that the cars may be coupled from the side of the draw-head instead of in front of and between the draw-heads, as heretofore. The cars may be coupled or uncoupled and the link may be removed while the draw-heads of the two cars are touching each other, which cannot be done by the devices heretofore generally in use. The projections *e* serve to prevent the draw-heads from being injured by jamming, and also serve as a guide to the link in coupling the cars, and thereby diminish the danger of uncoupling, and the pin-hole, being situated close to the face of the draw-head, partially does away with the use of bent links in coupling cars having draw-heads situated on different planes.

My improved coupling is simple and cheap, having no parts liable to get out of order.

Having thus described my invention, what I claim, and desire to secure by Letters Patent, 5 is—

1. A draw-head having a lateral link-opening and a re-enforce or brace upon the open or slotted side thereof, substantially as and for the purpose specified.
2. A draw-head having a lateral link-opening and projections or link-guides in front of and in line with the hole of the coupling-pin, substantially as and for the purpose specified.

3. The draw-head having the flaring lateral link-opening, the link-guides and re-enforce 15 arranged in front of and in line with the hole of the coupling-pin, and the transverse brace or re-enforce upon the slotted side of the draw-head, substantially as and for the purpose specified.

In testimony whereof I have hereunto set my hand.

JOHN F. WALLACE.
